(57) **CLAIM**

The ornamental design for a ring set, as shown and described.

DESCRIPTION

FIG. 1 is a front view of the ring;

FIG. 2 is a right view of the ring of FIG. 1, the left side view being a mirror image thereof;

FIG. 3 is a perspective view of the ring of FIG. 1;

FIG. 4 is a top view of the ring of FIG. 1;

FIG. 5 is a bottom view of the ring of FIG. 1; and,

FIG. 6 is a rear view of the ring of FIG. 1.

The ring is typically used as a piece of jewelry, and is placed on the fingers of individuals primarily for decorative purposes. The ring is comprised of a hollow circular body with a jewel centerpiece set on the ring.
